UNITED STATES PATENT OFFICE

MAURICE L. SINDEBAND, OF NEW YORK, N. Y., GEORGE N. TIDD, OF ELIZABETH, AND JOSEPH W. MILNOR, OF MAPLEWOOD, NEW JERSEY, ASSIGNEES TO GENERAL ELECTRIC COMPANY, A CORPORATION OF NEW YORK

COMMUNICATING SYSTEM FOR POWER-TRANSMISSION LINES

Original application filed January 28, 1920, Serial No. 354,602. Patent No. 1,724,112, dated August 13, 1929. Divided and this application filed November 25, 1927. Serial No. 235,430.

The present invention relates to communicating systems for power transmission lines and more particularly to a system for telephoning over a line employed to transmit power. Such a system is disclosed in our copending application Serial No. 354,602, filed January 28, 1920, (which issued as Patent 1,724,112, August 13, 1929), of which the present application is a division.

- 10 Alternating transmission lines have long since been employed to transmit power to points distant from the source of power. In order properly to operate these systems and to render them effective, it is desirable that 15 some form of reliable, private communicating system, such as the telephone, be provided between the power supply station and the consuming station or stations. Heretofore it has been suggested that telephone communication may be transmitted to some extent over power lines by superimposing voice frequency currents upon the power frequency currents of the transmission line, as disclosed 20 in the patent to Bedell No. 715,537. As indicated in that patent, however, the transmission of voice frequency over power transformers is unsatisfactory owing to various causes, among which may be mentioned the inability to completely remove harmonics of 25 the power system from a receiver without removing voice frequency currents as well. Such a system, in which a receiver is not responsive to voice frequencies only, is obviously of little practical value.
- 30 The present applicants have found that if modulated frequencies, upward of 5000 cycles, be superimposed on a power line and properly tuned circuits employed, such modulated high frequency currents may be transmitted 35 over ordinary power transformers to receivers tuned to the frequency of the transmitted signal and that in the received signal will be unaffected by the power frequency current.
- 40 The novel features which are believed to be characteristic of the present invention are set forth with particularity in the appended claims. The invention itself, however, will best be understood from reference to the following specification when considered in con-

nnection with the accompanying drawing in which the single figure shows a diagrammatic view embodying the features of our invention.

While the invention is applicable to an alternating current transmission line of any number of phases, we have shown it applied to a three-phase system. In the figure the power is adapted to be supplied to the transmission line through conductors 1 supplied by a suitable generator 2 and a step-up transformer 3. The secondary winding of the latter is connected to the three-wire transmission line indicated at 4, 5 and 6. The other end of the transmission line is shown connected to the primary winding of a step-down transformer 7, the secondary winding of which is connected to lines 8 which are connected to the load. The system thus far described is one commercially employed for high tension transmission. We employ the power conveying line as the signaling line by suitably coupling transmitting means at at least one station and receiving means at the other station, or, if desired, a receiver and transmitter may be employed at both stations.

At station 9 we have shown a generator 10 of alternating current having a frequency different from the frequency of the power current supplied to the lines 4, 5 and 6. For example, if the power frequency is 60 cycles per second the frequency of generator 10 is at least 5000 cycles or higher. The generator 10 is shown connected to a microphone or transmitter 11 which is adapted to modulate the high frequency current supplied to the high tension side of transformer 3 by generator 10. The latter is connected to one phase of the lines 1 by means of a current transformer of which one winding is designated 12.

In order substantially to prevent the power current from reacting on the transmitting circuit, the means shown at 13, 14 may be employed. It will be seen that inductance 13 and capacity 14 are connected in parallel across the winding 12 and these impedances are designed or adjusted for parallel resonance, for example, to be anti-resonant at 100

the frequency of the generator 10. This means that with the values of frequencies above assumed the combined impedance offered to the signal current at say 5000 cycles by the elements 13, 14 will be practically infinite, although the impedance offered by the last mentioned elements to the passage of the power current will be comparatively low. This means that so far as the 10 passage of signaling current in the transmitting circuit is concerned the set 13, 14 is substantially of no effect. On the other hand, practically all of the lower frequency current introduced into the local receiving circuit by the winding 12, passes through the elements 13, 14 by virtue of the comparatively low impedance of the latter at the power frequency.

The receiving means at station 15 is shown 20 as comprising a current transformer 16, having windings connected to the low tension side of transformer 7 and to two phases of the lines 8, an inductance 17 and capacity 18 in all respects similar to the corresponding 25 elements 12, 13 and 14 at the station 9. A telephone receiver 19 is connected in series with winding 16 and a crystal detector or other suitable rectifier 16'. An inductance 20 and capacity 21 designed for parallel 30 resonance at the frequency of the generator 10 may be shunted across the receiver 19 for the purpose of shunting out any power frequency current which may pass the antiresonant set 17, 18.

35 The impedances 22, 23 are preferably so designed or adjusted that the receiving circuit containing the receiver 19 will be tuned to or resonant at the frequency of generator 10 whereby a maximum amount of signaling 40 current will flow through receiver 19. Impedances 22, 23 are also preferably designed or adjusted for series resonance at the signaling frequency. With such design the combined impedance 22, 23 will materially restrict the flow of any power frequency current which may pass the set 17, 18.

In operation, it is assumed that the lines 4, 5 and 6 are carrying current at 60 cycles. If the operator at station 9 speaks into the 50 device 11 thus modulating the high frequency current supplied by generator 10 the sound vibrations will be reproduced at 19 in a manner which will be apparent to those skilled in the art. Since the receiving circuit at station 15 is tuned to the frequency of the generator 10, the operator at 15 will hear the transmitted message by means of the receiver 19. Due to the shunts 17, 18 and 20, 21 as well as the impedance offered 55 to the power current by the elements 22, 23 the receiver 19 will be free from any noise which would otherwise be caused by the power current. Signaling from station 15 to station 9 may be accomplished if desired in 60 a similar manner.

It will be observed that, with the arrangement shown, the signaling current is impressed upon a circuit which includes the conductor with which the current transformer 12 is associated, the upper and lower primary windings of transformer 3 and the source 2 of power current. Thus the transformer primary windings mentioned are connected in parallel with one another with respect to the source of signaling current and each is connected in series relation in a signaling current circuit with the corresponding winding of the source 2 and the secondary of the current transformer 12. As a result of this connection a high frequency carrier electromotive force is produced between the terminals of each of the primary windings mentioned. On the secondary side of transformer 3, signaling current circuits may be traced in which the secondary windings of the transformer, the conductors 4, 5 and 6 and the primary windings of transformer 7 are connected in series relation. Signaling currents transmitted through such a circuit are in turn impressed upon a circuit associated with the receiver which includes one of the secondary windings of transformer 7 the two conductors with which current transformers 16 are associated and any load devices which may be connected between these conductors.

It will be appreciated from the above description that we have provided a communicating system in which the power conveying conductors alone are employed to convey the signaling current without any substantial interference with the power transmission. No line wires, other than the power lines, are required so that the installation as well as maintenance costs are minimum. Furthermore, by virtue of the sets 13, 14; 17, 18; 20, 21 and 22, 23 which are designed or adjusted for parallel or antiresonance at the signaling frequency employed there is practically no noise caused in the receiving instrument by the low frequency power current.

What we claim as new and desire to secure by Letters Patent of the United States is:

1. A combined power and telephone system comprising in combination a source of alternating current power having a low frequency, a transformer, a transmission line, said transformer having a winding connected across said source of alternating current power and a second winding connected across said transmission line, means for producing a high frequency carrier electromotive force across one of said windings, said electromotive force having a frequency materially higher than the usual voice frequencies, means for modulating said carrier electromotive force with currents of voice frequency, a carrier current receiver which is responsive to electromotive forces produced across the other of said windings of said transformer and adapted to reproduce said voice frequen-

cies and means for excluding power currents from said receiver.

2. A combined power and signal system, comprising in combination a source of alternating current power having a low frequency, a transformer having a pair of windings, a transmission line, the terminals of one of said windings being connected to opposite sides of said source and the terminals of the other of said windings being connected across said transmission line, means for producing a carrier frequency electromotive force between the terminals of one of said windings, said electromotive force having a frequency of at least 5000 cycles, whereby said carrier frequency electromotive force appears between the terminals of said other winding, means for modulating said electromotive force in accordance with desired signals, a carrier current receiver connected to respond to said carrier frequency electromotive force appearing between the terminals of said other winding, said carrier current receiver being adapted to reproduce said signals, and means for excluding currents of the power frequency from said receiver.

3. A combined power and communication system comprising in combination a source of alternating current power of low frequency, a power transformer having primary and secondary windings, the primary winding being connected to said power source and the secondary winding being connected to a power transmission line, means for supplying a signaling current having a frequency materially higher than the usual voice frequencies to one of said transformer windings in such a way that the winding to which the signaling current is supplied is connected in series in the signaling current circuit, means for modulating said signaling current at an audio frequency, and a receiver coupled to a circuit supplied with power current from the secondary winding of said transformer in such a way as to have impressed thereon signaling current transmitted through a circuit in which the secondary winding of the transformer is connected in series, said receiver being responsive to the signaling frequency only and adapted to reproduce current of the modulating frequency.

4. A combined power and communication system comprising in combination a source of alternating current power of low frequency, a transformer having primary and secondary windings, the primary winding being connected to said power source, and the secondary winding being connected to a power transmission line, a source of signaling current having a frequency materially higher than the usual voice frequencies, means for inductively coupling said source of signaling current to a signaling current circuit which includes one of said windings in series therein, means for modulating said sig-

naling current, a signal current receiver and means for impressing upon the receiver signaling currents which are supplied thereto through a circuit in which said other winding is connected in series, said receiver being responsive to the signaling frequency only.

5. A combined power and communication system comprising a source of alternating current power of low frequency, a transformer having primary and secondary windings, the primary winding being connected to said power source and the secondary winding being connected to a transmission line, means for supplying modulated high frequency signaling currents having a frequency of at least 5000 cycles to a signaling current circuit which includes one of said transformer windings in series, a signal current receiver, and means for impressing upon said receiver signaling currents supplied through a circuit which includes the other transformer winding in series therein, said receiver being responsive to the signaling frequency only, and being adapted to reproduce currents corresponding to the modulations of the signaling current.

6. A combined power and communication system comprising in combination a source of alternating current power of low frequency, a transformer having primary and secondary windings, one of said windings being connected to said source and the other of said windings being connected to a power transmission line, means for supplying modulated signaling currents having a frequency higher than the usual voice frequencies to a circuit which includes one of said windings in series therein, a signal receiver, and means for supplying signaling currents to said receiver through a circuit which includes the other of said windings in series therein, said receiver being responsive to the signaling frequency only, and being adapted to reproduce currents corresponding to the modulations of the signaling currents.

7. A combined power and communication system comprising a source of alternating current of low frequency, a transformer having primary and secondary windings, one of said windings being connected to the source of power and the other of said windings being connected to a transmission line, a transmitter arranged to supply modulated signaling current having a frequency above the range of the usual voice frequencies to a circuit which includes one of said windings in series therein, a signal receiver, means for supplying signaling currents to said receiver through a circuit which includes the other of said windings in series therein, means for excluding power frequency currents from said transmitter, and means for excluding currents from said receiver having a frequency different from the signal frequency.

8. A combined power and communication

system comprising a source of multiphase alternating current power of low frequency, a transformer having sets of multiphase primary and secondary windings, the primary windings being connected to said source and the secondary windings being connected to a power transmission line, means for supplying to at least two of one set of said windings modulated signaling currents having a frequency materially higher than the power frequency, a signal receiver, and means for supplying to said receiver signaling current transmitted through at least two of the other sets of windings, the connections being so arranged that the windings to which signaling currents are supplied are connected in series with the source of signaling currents and in parallel with one another, and the windings which serve to transmit signaling currents to the receiver are connected in series relation in a signaling current circuit with which the receiver is associated.

In witness whereof, we have hereunto respectively set our hands the 19th day of November, 1927, the 15th day of November, 1927, and the 17th day of November, 1927.
